ELBOW CONNECTION FOR USE WITH SPARK PLUGS

Buford Wagoner Hulfish, Newark, N. J., assignor
to Victor Aircraft Company, Inc., Newark, N. J.,
a corporation of New Jersey

Application October 6, 1943, Serial No. 505,256

2 Claims.

(Cl. 174—35)

This invention relates to improvements in elbow connections for use with spark plugs and more particularly to an elbow joint especially adapted for use with the spark plugs of aircraft.

The present war has developed mass production of aircraft engines with the result that such engines all use radio shielded spark plugs, which are identical in physical size, shape, and connection detail. They, also, employ identical spark plug elbows, which consist of a casing only, through which the ignition lead with its insulation runs unbroken to the spark plug. These elbows, however, are produced with different angular bends. They, also, use connector assemblies, consisting of an insulative sleeve, a ferrule, and a spring, which serve to secure the end of the ignition lead at the spark plug and make electric connection, and provide a long flash-over distance to grounded metallic radio shielding members. Spark plugs, elbows, and connector assemblies at the present time are made in huge quantities, and their physical shape and size have become practically standard for the present and near future.

Many failures of lead insulation occur in present elbows, or between elbows and spark plugs. They are due to heat and the reduction of the dielectric strength of the rubber insulation when in tension, as it is in the outer portion of the bend through the elbow. Also, the failures are sometimes due to moisture entering at the connection of the elbow casing. In still other cases, faults are due to the failure of the seal around the internal insulation of the spark plug, which allows oil and gas from the engine cylinder to pass into the elbow and along the lead conductor under the insulation covering, with detrimental effect.

The primary purposes of the present invention is to provide a novel elbow connection designed to eliminate such defects.

Another object is to supply an elbow which may be installed in place of the hollow elbow now in use, without the necessity of shortening the flexible radio shielding of the ignition lead extending from the elbow to the ignition manifold. This feature provides two advantages; first, the elbow may be applied to ignition harnesses made for existing hollow elbows with a minimum of labor and without certain tools and equipment for shortening the flexible shielding, and second, the elbows can be used to replace hollow elbows on engines which are in

service when facilities for shortening the flexible shielding are not available.

Another object is to furnish an elbow with built-in insulating material which adheres so tightly to the conductor assembly that a seal is created against the passage of liquid or gas, from an internally leaking spark plug, to the cavity provided for the ignition lead connection, hence, along the conductor of the lead under its insulation.

A still further object is to provide an elbow having a seal against entrance of liquid or gas where the elbow casing engages the top edge of the spark plug shielding, accomplished by arranging additional insulation material along the area of contact with the plug edge.

A still further object is to supply an elbow having a seal against entrance of liquid or gas where the elbow casing engages the end of the flexible lead shielding, which is achieved by extending the insulating material slightly beyond an end of the elbow casing so that it will engage part of the end of the shielding, all the way around.

A further object is to provide an elbow in which my improvements are incorporated and having a cavity to accommodate the ignition lead connection so that it will take the connector assembly now in common use.

A still further object is to produce a simple and practical elbow connection and yet one which will be exceedingly effective for the purposes for which it is designed.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings:

Fig. 1 is a side elevation of my improved elbow assembly.

Fig. 2 is an enlarged longitudinal vertical sectional view of the same.

Fig. 3 is another side elevation taken at right angles to Fig. 1 and with the nut of the assembly not shown.

Fig. 4 is a longitudinal sectional view of a modification of the elbow assembly shown connected to a spark plug and ignition harness.

In the embodiment of the invention illustrated in Figs. 1 to 3, inclusive, 5 designates an elbow shaped casing formed of any suitable conducting material, such as metal, and having an upper

arm 6 provided with external screw threads 7. The casing, also, includes a leg 8 terminated in a flared mouth or flange 9.

In the manufacture of my elbow assembly, I mold suitable insulating material 10, such as synthetic rubber, within the casing, and before doing so, arrange a conductor assembly 11 partly within the latter. This assembly comprises a threaded stud 12 to which is connected a conductor 13 small enough in diameter to permit it to bend after the assembly of the elbow is completed. I prefer to use a conductor of a diameter of about $\frac{1}{32}$ " instead of the conventional conductors which are about $\frac{3}{32}$ " in diameter. The conductor is secured at its upper end to a conductor disk 15 provided with a blind hole 15x and a threaded aperture 16 for a purpose herein-after disclosed. To facilitate manufacture, the internal conductor assembly is secured at the threaded end 12 and, also, near the opposite end by means of a threaded stud, not shown, which engages the threads of the aperture 16 while the insulating material which is in plastic condition is being injection-molded into the casing. This assures that the conductor assembly will be positioned as desired. In the molding an extension 17 is formed below the casing.

This extension either during the molding or afterwards is positioned within a ceramic sleeve 18 that has a recess 19 at its lower end for the accommodation of a nut 20 which engages the threaded end of the conductor assembly to secure the sleeve in place, and, also, serves as anchoring means for the upper end of a conductor spring 21. During the molding, the insulation is provided with a circular bead 22 which fills the flared mouth 9. Also, during the molding, a plug (not shown) having a dowel pin to fit the hole 15x and secured to the contact disk by the threaded aperture 18, serves to form a cavity 23 within the arm 6 for the reception of the ignition lead. Furthermore, during the molding, the insulation is provided with a circular flange 24 which is formed of the insulating material and projects beyond the end of the arm 6.

The assembly is completed by a nut 25 which cooperates with the flange 9 in securing the elbow to the casing of the spark plug. It will be noted that the nut due to the shape and length of the leg 8 can be backed off the flange 9 to facilitate inspection of the joint.

In Fig. 4 the construction of the elbow assembly is the same as the one illustrated in Fig. 3 with the exception that the leg 8a projects at a different angle from the arm 6a. In Fig. 4 the end portion 26 of the ignition harness 27 is shown extending into the elbow assembly with its spring 28 contacting the disk 15a. Furthermore, in this view, the nut 29 of the harness is shown clamping the end 30 of the flexible radio shielding of the harness against an end of the casing and the projecting flange 24 of the insulation. Here, also, the nut 25a of the assembly is shown in threaded engagement with the casing 31 of the spark plug and the spring 21a is shown in contact with the electrode 32 of the plug.

The synthetic rubber which I propose to use as insulation in the elbow assembly is somewhat flexible in its final cured state. Thus, by providing a flexible conductor 13 embedded in the synthetic rubber, the portion of the assembly which projects beyond the casing of the elbow will not be rigid. Therefore, it can be bent away from the straight axis of the leg of the elbow. This feature of the assembly will greatly facil-

tate the installation and removal of the elbow from the spark plug in cases where there may be other adjacent engine parts which provide interference. It will, also, be an advantage in the case of a 70° elbow.

Other advantages of the use of the smaller diameter conductor 13 are: less heat conducted into the insulation and the connection cavity 23; greater thickness of insulation between the conductor and casing, and somewhat smaller condenser value for the elbow.

Economical and effective use is made of the insulating material within the elbow by providing less thickness where other insulation already exists, and by providing greater thickness of insulation where no other insulation exists, that is, between the outer metallic casing and the internal conductor 13. Accordingly, the insulation is thinner around the cavity 23 toward the open end where insulation is present on the ignition lead itself, and is thicker around that portion of the cavity that will contain the uninsulated spring contact 28 on the end of the connector assembly.

Disconnection of the ignition lead from the elbow is obtained simply by unscrewing the nut 29 which secures the flexible shielding to the casing of the elbow. Therefore, the ignition lead may be disconnected from the elbow, without previously removing the elbow from the spark plug. This is advantageous especially in the case of the 70° elbow which cannot be removed from the spark plug when the ignition lead is attached unless sufficient slack or additional length is provided in the ignition lead. The shorter the length of the flexible ignition lead from the elbow to the ignition manifold (not shown), the more serious the task of removing the elbow becomes without disconnecting the ignition lead at the elbow. The condition arises from the fact that the connection end of the elbow heretofore used and which extends into the spark plug is rigid, and, therefore, must be withdrawn from the spark plug along a straight line, and to achieve this path, slack must be available or stretching occurs in the ignition lead beyond the elbow unless it can be disconnected.

As hereinbefore mentioned, the nut 25, 25a may be unscrewed from the spark plug and moved back to a position where the contact between the elbow casing and the spark plug shielding can be viewed. This is desirable for inspection purposes, and particularly in cases when the voids, remaining in the spark plug cavity after insertion of the connection end of the elbow, are to be filled with an insulation fluid compound. Such an expedient is frequently used and inspection is required to see that the voids have been filled and that no excess compound exists at the joint to impair the making of metal to metal contact between the spark plug and elbow casings.

The only spring 21, 21a in the elbow assembly is removable and replaceable with the nut (20). This saves an elbow assembly from being discarded when a spring loses its temper or becomes broken.

The ceramic sleeve insulation 18 which goes into the spark plug cavity is, also, capable of being replaced in case of damage to a sleeve.

As the contact disks 15, 15a have rounded edges, they are much better in high frequency and high voltage construction than disks having square edges.

From the foregoing, it is believed that the con-

struction and advantages of my elbow assembly will be clearly understood without further description, and it will, also, be understood that the embodiments of my invention herein disclosed are to be taken as examples only as the invention may be embodied in other constructions falling within the terms of the appended claims.

What I claim and desire to secure by Letters Patent is:

1. An elbow assembly for use with a shielded spark plug, comprising an elbow shaped casing having an arm and a leg, flexible insulating material filling said leg and lining said arm, said insulating material forming a substantially cylindrical flexible projection depending from said leg, a contact element positioned in the casing and insulated by said material, a flexible conductor extending from said element and embedded in the insulating material in said leg and projection, a stud connected to the flexible conductor and extending beyond said projection,

and a sleeve of rigid insulating material surrounding said projection, spaced from said leg and removably secured to said threaded stud.

2. An elbow assembly for use with a shielded spark plug, comprising an elbow shaped casing of conducting material having an arm and a leg, flexible insulating material molded within the casing, filling the said leg and lining said arm, said insulating material forming a substantially cylindrical projection depending from said leg, a contact element positioned in the casing at the inner end of the lining, a flexible conductor extending from said element and embedded in said insulating material and said projection, a threaded stud connected to the flexible conductor and extending beyond said projection, a rigid sleeve of insulating material surrounding said projection, a nut having threaded engagement with the stud and removably securing the sleeve in position, and a contact element projecting from said nut.

BUFORD WAGONER HULFISH.
